John Richardson, Simplified Plan.
Little Poland

The Plan is referred to on these Little Poland, and making part of
 the same containing a description in the words of himself John Richardson
 himself of his improvement in the setting out plan.

To all whom it may concern

I B. it is known that at Little Poland in the County of Franklin
 in said State of Pennsylvania, have made certain improvements in the
 agricultural implement used on the surface of setting in raising grain which
 instrument is improved by me & designated a setting out plan. And
 I do hereby declare that the following is a full and exact description thereof
 concerning had to the drawing which accompanies & makes a part
 of this specification. - To make a frame of three pieces of timber A.A.
 A nail of which should be about 300 feet long & about three inches
 square. They are joined by being halved together at the three angles
 in the manner shown in the drawing. The piece A is the front one
 of the frame & this and the two side timber are halved together at their
 ends, but the two timber cross each other at the angle B at two feet
 from their ends. The projecting end of these are to receive the standards
 C.C. which support the handle D.D. Immediately under the angle
 formed at the back end and projecting forward of it is placed a door
 or wedge shaped board bound provided with a shank and counter and
 hewed onto the same timber by two bolts. The ends of which are sawn
 at A.A. - The shank and mouth board projects generally toward
 the front of the implement as seen at B.B. - To the side A.A. of each
 bolt or shank place on each side - They are made in the usual
 form of scythes took on about four inches on the face & extends
 about eight inches below the frame. The shank which passes thro'
 the frame may be fastened by a nail or peg as at C.C. The both
 or shanks are placed at right angles with the sides which project to them

The proper slope of the machine is known from trial. The machine is drawn by two horses, the simple beam, with every attachment to a bar or beam, is one foot in length which allows the proper forward of the timber & to a suitable distance. The use of the chevron chain & is manifest upon inspection. The height and distance of the handles D.D. need in the same as in ploughs or cultivators generally.

In using this instrument the ground is first prepared by ploughing, and harrowing in the usual way when this has been done and the land drawn the land is staked off at distances of a little upward, of seven feet. These stakes serve as guides for the centre or plough part of the cultivator & the width on the side timbers then form the ground into furrows, of the most convenient and suitable width for the advantageous growth of the grain. I do not claim as my invention the individual parts of this machine as I have described them, but what I do claim is that general arrangement and combination of the whole which gives to it that character by which it is distinguished from other cultivators or harrows. A principal feature by which it is thus distinguished is the cross direction on which the triangle is drawn forward & the position of the double mould board and its application in the centre by which the timbers are divided.
